Zacey & Zacey, Attorney

UNITED STATES PATENT OFFICE.

GEORGE WORDINGHAM, OF MILWAUKEE, WISCONSIN.

SOFT-SHIRT-COLLAR PROTECTOR.

Application filed June 30, 1925. Serial No. 40,577.

This invention relates to an improved soft shirt collar protector particularly designed for use by laundries, dry cleaners, or the like, and seeks, among other objects, to provide a device which will prevent the mussing or wrinkling of the soft collar of a fresh laundered shirt and retain the collar in shape during the packing and delivery of the shirt.

10 The invention seeks, as a further object, to provide a device which may be readily applied.

And the invention seeks, as a still further object, to provide a device which will be 15 inexpensive and yet will efficiently serve its intended function.

Other and incidental objects will appear hereinafter.

In the accompanying drawings:
20 Figure 1 is a fragmentary elevation showing my improved protector applied beneath the collar of a conventional soft shirt, the collar being partly broken away.

Figure 2 is a perspective view showing the 25 device in detail and illustrating the shape of the device when applied within a collar.

Figure 3 is a plan view showing the normal shape of the device.

In carrying the invention into effect, I 30 employ an oblong strip 10, of tag, cardboard or the like. The strip is thus more or less resilient and, as will be observed, said strip is preferably of uniform width. In the present instance, I have shown the 35 strip as being relatively narrow but this detail, as well as the length of the strip, may, of course, be varied to suit the requirements of use, and formed in the strip, near the ends thereof, are like longitudinal slots 11.

40 The strip is thus double-ended.

In Figure 1 of the drawings, I have shown the device in position beneath the

soft collar of a conventional shirt 12. The collar is indicated at 13 and, as is prevalent, is of the same soft material as the shirt. To 45 apply the device, the strip 10 is arranged to encircle the neck band of the shirt beneath the collar, when one end portion of the strip is inserted through the slit in the other end of said strip. The loop thus 50 formed is then contracted more or less tightly about the neck band, and, as will be perceived, the edges of said slit will frictionally coact with the end portion of the strip for preventing the separation of the ends of the strip and holding the loop in adjustably contracted position. Thus, the strip will be 55 retained beneath the collar to support the collar and prevent the creasing or mussing thereof during the packing and delivery of the shirt, and since the strip is double-ended, either end of the strip may, of course, be inserted through the slit in the other end thereof. The convenience of the device is 60 thus materially enhanced.

Having thus described the invention, what I claim is:

In combination with a shirt having a soft collar, of means for supporting and maintaining the natural set of the collar, the 70 same consisting of a narrow strip of cardboard, having a longitudinal slit adjacent an end of greater length than the width of the opposite end of the strip and bent upon itself to encircle the neck band of the shirt 75 and disposed beneath the collar, and having the opposite end portion of the strip passing through the longitudinal slit, whereby a flare is imparted to the support corresponding with the natural set and flare of the shirt 80 collar.

In testimony whereof I affix my signature.

GEORGE WORDINGHAM. [L. S.]
